UNITED STATES PATENT OFFICE

WILLIAM T. McCULLOUGH, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed December 25, 1926, Serial No. 157,005. Renewed September 10, 1931.

- This invention relates to improvements in mining machines, and more particularly to coal cutting machines of the type mounted on track guided trucks adapted to cut a kerf 5 in front of and to each side of the track along the mine bottom or at various elevations with respect thereto, and also adapted to be swung into various positions for cutting shearing or angular kerfs.
- 10 The principal objects of my invention are to provide a new and improved machine, of the class described, constructed with a view towards maximum efficiency, simplicity, compactness, and adaptability to varying 15 conditions of cutting, wherein the cutter arm may be positioned for cutting the usual slabbing or arcuate kerfs in several planes parallel to the mine bottom including planes below the level of the track; wherein the cutter 20 arm may be yieldably adjusted for cutting along an uneven bottom; and wherein said cutter arm may cut angular or vertical shearing kerfs at either side of the longitudinal center line of the cutter arm.
- 25 Further objects and advantages will appear from time to time as the description proceeds.
- The invention may be best understood by 30 reference to the accompanying drawings wherein:
- Figure 1 is a plan view of the front end of the machine in partial section;
- Figure 2 is a plan view of the complete machine with the cutting element disposed 35 for cutting a shearing kerf, with parts broken away and in section to more clearly show the details of my invention;
- Figure 3 is a side elevation of the machine 40 as shown in Figure 2, with parts broken away to show the turn-table gearing;
- Figure 4 is a side view of the complete cutting mechanism showing both the cutter head and the tilting mechanism in section;
- 45 Figure 5 is a front end view of the machine with the cutter arm in position for cutting a shearing kerf and with parts broken away in section to more clearly show the details of my invention; and
- 50 Figure 6 is a rear end detail view of the tilting mechanism with parts broken away and in section.
- Referring now in particular to the details of the drawings, the device embodying my invention includes a main frame or truck 10 mounted on suitable track wheels 13, 13 in a usual manner. The main frame or truck 10 has a turntable 12 mounted thereon adjacent the forward portion thereof in such a manner that its axis of pivotal movement 60 is between the axes of the track wheels 13, 13. Cutting mechanism, generally indicated by reference character 11, is mounted on the turntable 12 on suitable trunnion supports adjacent one end of said turntable and yieldably adjustable with respect to said turntable about these trunnion supports to permit tilting of said cutting mechanism to accommodate said cutting mechanism to an uneven mine bottom or irregularities in the coal seam 70 in a manner which will hereinafter be described.
- The cutting mechanism 11 includes a motor 60 of an ordinary type and a frame member or cutter head 17 disposed forwardly of 75 said motor for rotation with respect thereto about a longitudinal axis. A suitable cutting element including a projecting cutter arm 14 is carried by the cutter head 17 for movement therewith and for adjustment with 80 respect thereto.
- The cutter head 17 has a rearwardly extending neck 18 adapted to be journaled within a bearing 19 formed internally of a housing 20 secured to and extending forwardly 85 of the casing for the motor 60 which permits said cutter head to be adjusted with respect to the truck 10 about an axis extending longitudinally of the cutting mechanism 11.
- The cutter arm 14 is provided with a cutter 90 chain 15 guided thereabout in suitable guides 16 in a usual manner for movement therewith in a closed orbital path.
- With reference in detail to the means for supporting the cutter head 17 for movement 95 about an axis extending longitudinally of the cutting mechanism 11 and housing 20, an auxiliary outboard supporting bracket 23 is secured to the top surface of said housing and extends forwardly therefrom over said cutter 100

head and has a forward end 22 journaled on a stud 21 formed integral with and extending forwardly of the forward end of said cutter head. A flange 24 is formed integral with 5 and extends outwardly from the outer periphery of the neck 18 of the cutter head 17 and is guided in a suitable guide groove 25 formed in the undersurface of the outboard supporting bracket 23 adjacent the forward end of 10 the housing 20 for holding said cutter head in position with respect to said housing, and permitting relative rotation of said cutter head with respect to said housing.

A segmental worm gear 84 is secured to the 15 outer periphery of the neck 18 of the cutter head 17 forwardly of the flange 24 by means of suitable studs and nuts or cap screws in a usual manner. The segmental worm gear 84 is meshed with a worm 85 which is mounted 20 on a transversely extending shaft 86 disposed above said segmental worm gear and mounted in suitable bearing supports formed integral with the outboard supporting bracket 23 (see Figs. 1, 4, and 5). Suitable means 25 are provided for rotating the shaft 86 and worm 85 which may be of any type well known to those skilled in the art, such as a hand crank of a usual construction (not shown) adapted to fit on a squared end of 30 said shaft.

It may thus be seen that the cutter head 17 is rigidly supported for rotation about an axis extending longitudinally of the housing 20 and that said cutter head may be so adjusted by means of the worm 85 and worm gear 84 in an obvious manner and held in any desired position of adjustment during the cutting operation by means of said worm and worm gear which are of the self-locking type.

40 The means for supporting the cutting element and cutter arm 14 by the cutter head 17 for pivotal movement with respect thereto about an axis perpendicular to the axis of rotation of said cutter head, and for movement 45 towards and away from said cutter head in a plurality of parallel planes is as follows:

The cutter arm 14 is carried by an extension arm 30 of a revoluble cutter arm support 31 in a usual manner. The cutter arm support 50 31 is carried by suitable guides for movement towards and away from the cutter head 17 in a manner which will hereinafter be more fully described and is mounted concentrically of a hub portion 32 of a cutter chain drive 55 sprocket 33, which sprocket is adapted to mesh with the cutter chain 15. The cutter chain drive sprocket 33 being journaled within the cutter arm support 31 is keyed on the outer end of a splined drive shaft 34 which is 60 rotatable about an axis disposed perpendicularly to the axis of pivotal movement of the cutter head 17. A nut 35 is threaded on the outer end of the splined drive shaft 34 and abuts the outer end of the sprocket 33 for 65 holding said sprocket on said shaft.

A thrust ring 36 is threaded on the inner end of the hub portion 32 of the cutter chain drive sprocket 33 and has bearing support in a suitable recess formed in the inner surface of the cutter arm support 31 and forms a means for holding said cutter chain drive sprocket in said support.

70 The splined drive shaft 34 has a slidable drive connection in a hub 66 of a bevel gear 65, which bevel gear is driven from the motor 60 in a manner which will hereinafter be more fully described, for driving the cutter chain 15 about the cutter arm 14. The hub 66 of the bevel gear 65 is journaled in and extends through a bearing 67 formed in the cutter head 17, the shoulder of which bearing serves as a thrust bearing for said bevel gear.

75 The cutter arm support 31 is provided with an annular recess 38 formed in the inner surface thereof, which annular recess forms a bearing support for an annular support member 37. The annular support member 37 is in turn slidably supported by suitable guides extending from the cutter head 17 for movement towards and away from said cutter 80 head in a manner which will hereinafter be more fully described.

85 A flange 39 is formed integral with the outer periphery of the annular support member 37 and is adapted to be guided in a suitable guide 90 40 formed by a shouldered inner portion of the cutter arm support 31 and an annular retaining ring 31a secured to the cutter arm support 31 and abutting the upper side of the flange 39. Thus the cutter arm 14 is so mounted as to be rotatably moved with respect to the annular support member 37 and cutter head 17 about the axis of rotation of the cutter chain sprocket 33.

95 Referring now in particular to the means wherein the annular support member 37 is carried by the cutter head 17 for movement towards and away from said cutter head, a pair of guide members 80, 80 extend outwardly from the rearward portion of the 100 annular support member 37 and are connected thereto by means of integral supporting ribs 80a, 80a formed integral with the top portion of the annular support member 37 and extending angularly outwardly and rearwardly from the forward end thereof.

110 The guide members 80, 80 are provided with suitable inwardly formed grooves 82, 82, which grooves are adapted to engage suitable tongues 83, 83 formed integral with and 115 extending outwardly from guide arms 81, 81. The guide arms 81, 81 extend from opposite sides of the cutter head 17 and are connected thereto by means of suitable integral supporting ribs 81a, 81a and extend from a position disposed above the axis of rotation of the cutter head 17 to a position below said axis of rotation of said cutter head when 120 said cutter head is positioned for cutting a horizontal kerf in the mine wall to permit 125 130

the cutter arm 14 to be rigidly supported when cutting a kerf adjacent the mine bottom or at various elevations with respect thereto.

- 5 The forward portion of the annular support member 37 is supported by the cutter head 17 for movement with respect thereto by means of a screw or threaded shaft 41 disposed forwardly of the splined drive shaft 34 in alignment with said shaft. A head 50 on the outer end of the shaft 41 is shouldered in a recess 51 formed in the surface of the annular support member 37 abutting the cutter arm support 31. The opposite end of the shaft 41 is threaded in a hub of a worm gear 44, which worm gear is supported and journaled in its hub in a suitable bearing support 76 formed integral with the cutter head 17 adjacent the forward end thereof.
- 10 15 20 25 30 35 40 45 50 55 60 65 70 75 80 85 90 95 100 105 110 115 120 125 130
- 20 The guide members 80, 80, guide arms 81, 81, and threaded shaft 41 thus afford a sliding support for the annular support member 37 and cutter arm 14 whereby said cutter arm may be supported for cutting along the mine bottom and may be adjustably moved towards and away from the cutter head 17 for cutting at various elevations with respect to the mine bottom.

A pinion 42 is carried in a suitable recess formed in the annular support member 37 and is keyed on the threaded shaft 41. The pinion 42 meshes with an internal gear 43 formed integral with the inner periphery of the cutter arm support 31, the upper side of which gear is adjacent the lower portion of the guide 40 when the cutter arm 14 is positioned to cut in a horizontal plane and forms the lower side of said guide.

It may thus be seen that rotation of the threaded shaft 41 will drive the pinion 42, which will in turn pivot the cutter arm 14 about the axis of the splined drive shaft 34 and that when the threaded shaft 41 is moved through the hub of the worm gear 44 in one direction or another that the cutter arm 14 will be moved towards or away from the cutter head 17.

A worm 45 on a shaft 46 extending longitudinally of the cutter head 17 and journaled in said cutter head meshes with and drives the worm gear 44. Suitable clutch jaws 77 are provided on the side of the worm gear 44 opposite the hub portion journaled in the bearing support member 76. The clutch jaws 77 are adapted to be engaged by clutch jaws 78 on a sliding clutch member 79 feathered on the shaft 41. The sliding clutch member 79 is provided with a hub extension 79a slidably in a suitable guide sleeve formed integral with the forward portion of the cutter head 17.

When the clutch jaws 78 are engaged with the clutch jaws 77, the threaded shaft 41 is driven by the worm gear 44 to pivotally move the cutter arm 14 about the axis of the splined

shaft 34. On the other hand, when the clutch jaws 78 are disengaged from the clutch jaws 77, rotation of the worm gear 44 will move the threaded shaft 41 through the hub of said worm gear in an obvious manner and vary the distance of the cutter arm 14 with respect to the axis of rotation of the cutter head 17.

It may thus be seen that a single extensible member has been provided for moving the cutter arm 14 towards and away from the cutter head 17 and for moving said cutter arm about an axis extending perpendicular to the axis of pivotal movement of said cutter head, which member is herein shown as being the threaded shaft 41 located midway between the guide arms 81, 81 and a new and improved means for adjusting the cutter arm 14 in a plurality of parallel planes towards and away from the cutter head 17 and for rotating said cutter arm 14 has been provided which is of a simplified, compact, and efficient construction.

A suitable locking means is provided for locking the cutter arm 14 in various fixed angular positions with respect to the cutter head 17 for permitting said cutter arm to be disposed to one side or the other of the track and dumped into the coal when in such a position in a usual manner which comprise a pin 52 slidably mounted in the annular support member 37 (see Fig. 5). The pin 52 is adapted to register with any one of a number of apertures formed in the cutter arm support 31. The pin 52 is operated by a suitable hand lever 53 in a usual manner, although said pin may be permitted to operate by its own weight by gravity for automatically locking and holding the cutter arm 14 in the desired position of adjustment.

Referring now to the drive connections from the motor 60 to the cutter chain drive sprocket 33 and the threaded shaft 41, said motor is provided with a motor shaft 59. A motor pinion 61 is secured to the forward end of the motor shaft 59. The motor pinion 61 meshes with and drives a spur gear 62 on the rearward end of a shaft 63 extending longitudinally through the neck 18 of the cutter head 17. The shaft 63 is supported in suitable bearings 68 and 69 formed integral with the neck 18 of the cutter head 17 in a suitable manner, and has a bevel pinion 64 keyed on its forward end which meshes with and drives the bevel gear 65, which bevel gear in turn drives the cutter chain 15 about the cutter arm 14 through the splined shaft 34 and sprocket 33 in a manner which has hereinbefore been described.

A spur gear 72 is freely mounted on the shaft 63 rearwardly of the bearing 69. Suitable clutch means are provided for connecting the spur gear 72 with the shaft 63, which may be of any suitable construction but which are herein shown as being friction clutch means

of the cone clutch type. Said clutch means includes an internal clutch member 71 formed integral with and extending rearwardly from the spur gear 72, which clutch member is 5 adapted to be engaged by an external clutch member 70 feathered on the shaft 63. The spur gear 72 meshes with and drives an idler gear 73, which idler gear is supported in a U shaped bearing bracket 74 in an ordinary 10 manner. The idler gear 73 meshes with and drives a spur gear 75 keyed on the rearward end of the longitudinally disposed shaft 46. Thus when the clutch member 70 is engaged with the clutch member 71, the shaft 46 will 15 be driven from the motor 60 at a frictionally controlled speed which will pivot the cutter arm 14 about the axis of the splined shaft 34 or adjust said cutter arm with respect to the cutter head 17, depending upon whether 20 or not the clutch jaws 78 are engaged with the clutch jaws 77.

Means are provided for supporting the cutting mechanism 11 on the turntable 12 whereby the cutter arm 14 may be angularly 25 adjusted with respect to the mine bottom about a horizontal axis, which means comprise studs 88, 88 extending from opposite sides of the housing 20 adjacent its central portion thereof but beneath its longitudinal axis. 30 The studs 88, 88 are journaled in suitable trunnion brackets 87, 87 secured to and extending upwardly and outwardly from the turntable 12.

The cutting mechanism 11 may be yieldably tilted about the axis of pivotal connection of the studs 88, 88 to the trunnion brackets 87, 87 by means of suitable yieldable tilting and support mechanism attached to the turntable 12 and secured to the rearward end of 40 the casing for the motor 60 which includes a frame member 90 secured to said turntable. The frame member 90 is provided with a worm and worm gear housing 91 formed integral therewith, which housing has a transversely extending shaft 92 journaled therein. The transversely extending shaft 92 has a worm 93 secured thereto, which worm meshes with and drives a worm gear 95 keyed adjacent the lower end of a vertically disposed 45 screw shaft 96. The vertically disposed screw shaft 96 is journaled in the worm gear housing 91 and a set nut 97 is threaded on its lower end and abuts the lower portion of said worm and worm gear housing. A nut 50 98 is threaded on the screw shaft 96 and is provided with a pair of studs 99 trunnioned in a beam member 100 for pivotal movement with respect thereto about an axis extending longitudinally of the cutting mechanism 11. 55 The beam member 100 is adapted to be slidably supported adjacent its ends in a guide frame member 101 extending rearwardly of the casing for the motor 60 on each side thereof. The beam member 100 is provided with 60 suitable upstanding and depending lugs ad-

jacent its ends on which are positioned compression springs 103, 103 disposed between the lower side of said beam member and an upper portion of the guide frame member 101 on suitable lugs extending upwardly therefrom and compression springs 103, 103 disposed between the top portion of said beam member and suitable lugs depending from retaining brackets 102, 102 so movement of said beam member along the screw shaft 96 70 will yieldably move the cutting mechanism 11 about the axis of the studs 88, 88 in an obvious manner. A suitable means is provided on the shaft 92 for rotating said shaft and moving the beam member 100 along the screw shaft 96, 75 which means may be of any type well known to those skilled in the art but which is herein preferably shown as being a hand wheel 94.

It may thus be seen that the cutter arm 14 85 may readily be adjusted about the axis of the studs 88, 88 for cutting at various angular positions with respect to the ground, and that the adjusting means for said cutter arm is yieldable to compensate for irregularities in 90 the coal seam and minimize the effect of shocks on the cutter arm 14 and the entire mining machine during cutting.

Referring now to the drive for the turntable 12 and means for feeding the cutter arm 95 14 in an arcuate path across the coal face, said turntable may be rotated to swing said cutter arm in an arc across the front and sides of the main frame or truck 10. Turning of the turntable 12 is independent of operation of 100 the cutting mechanism 11 and said turntable may be turned in any suitable manner but is herein shown as being turned by a motor 104 disposed at the rearward end of the main frame or truck 10. The motor 104 drives a 105 transverse shaft 105 through suitable gear reduction mechanism, generally indicated by reference character 106. A worm 107 on the transverse shaft 105 drives a worm gear 108 on a vertical shaft 109. A spur gear 110 on the lower portion of the vertical shaft 109 is driven by the worm 107 in a suitable manner. The spur gear 110 meshes with and drives a spur gear 111 journaled in the main frame or truck 10 in a usual manner. A spur pinion 115 112 is coaxial with and driven by the spur gear 111 and meshes with teeth 113 on the outer periphery of the turntable 12 for rotating said turntable.

It may be seen from the foregoing description that the cutter arm 14 is provided with a number of distinct and individual movements which are as follows:

First.—The entire cutting mechanism 11 may be turned about a vertical axis by means 125 of the turntable 12 for positioning the cutter arm 14 or for feeding said cutter arm along the coal face.

Second.—The cutter arm 14 may be swung about an axis coaxial with the cutter chain 130

drive shaft 34, for feeding said cutter arm vertically when making a shearing cut in the mine wall, or for positioning said cutter arm to one side of the truck for cutting a horizontal kerf in the mine wall to either side of the track, locking means being provided for locking said cutter arm in the desired position of adjustment with respect to the mine wall. Said second mentioned movement of the cutter arm 14 may be utilized for feeding said cutter arm when cutting horizontally if desired but is usually used only for positioning said cutter arm or for feeding said cutter arm vertically when shearing.

15 Third.—The cutter head 17 and cutter arm 14 may be rotated about an axis extending longitudinally of the cutting mechanism 11 for positioning said cutter arm for shearing or cutting in various angular positions with respect to the mine wall.

20 Fourth.—The cutter arm 14 may be moved into various planes of adjustment towards or away from the axis of rotation of the cutter head 17, for adjusting said cutter arm for shearing to either side of said axis of rotation of said cutter head or the main frame or truck 10, and for positioning said cutter arm for cutting at various elevations with respect to the mine bottom.

25 Fifth.—The cutter arm 14 may be yieldably adjusted about an axis extending transversely of the cutting mechanism 11, for adjusting the position of said cutter arm with respect to the mine bottom to permit said cutter arm to cut along an irregular mine bottom or in irregular seams of coal.

30 Machines constructed in accordance with my invention are operated in a usual manner and the operation of the device of my invention should now be clear to those familiar with the art. The machine may be driven from working place to working place on the track wheels 13 driven from the motor 104 at either a high or low speed in a manner well known to those skilled in the art and not herein shown or described in detail since it is no part of my present invention. The cutter arm 14 may be fed into the coal face by means of the track wheels 13 driven by the motor 104 or by means of a suitable flexible feeding member having connection with a suitable winding drum driven from the motor 104 in a usual manner (not shown).

35 As has before been stated, the cutter arm 14 may be fed across the face of the coal in an arcuate path by means of the turntable 12 or the threaded shaft 41, pinion 42, and internal gear or rack 43, and said cutter arm may be fed vertically by means of said threaded shaft, pinion, and internal gear or rack in a manner which has hereinbefore been fully described.

40 It is thus apparent that a new and improved machine of a simplified and compact construction has been provided having many

advantages heretofore unknown in the art which is so arranged as to cut adjacent the mine bottom or at various elevations with respect thereto, and which may also cut shearing or angular kerfs in the mine wall. 70 It may also be seen that the feature whereby the cutter arm 14 may be adjusted about an axis disposed forwardly of the axis of pivotal movement of the turntable 12 and parallel thereto when said cutter arm is positioned for cutting a horizontal kerf in the mine wall permits said cutter arm to be readily adjusted for cutting below the level of the track adjacent the mine bottom in front of and to each side of the track and that the device of my invention is thus particularly adapted for cutting in narrow rooms or driving entries. Furthermore, the fact that the device of my invention is so arranged that the cutter arm 14 may be yieldably supported for movement about a transverse axis disposed rearwardly of its rearward end permits said cutter arm to be readily adapted for cutting along irregular mine bottoms or in coal seams having irregularities therein and said feature minimizes the effect of the transmission of shocks from said cutter arm to the entire mining machine. 80 85 90

95 Although I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment 100 illustrated in the drawings, excepting as it may be limited by the appended claims.

105 I claim as my invention:

1. In a mining machine, a main frame, cutting mechanism rotatable about a vertical axis on said main frame, said cutting mechanism comprising an auxiliary frame having a cutter head rotatable therein about a horizontal axis, a motor disposed on said frame, driving mechanism disposed in said cutter head and rotatable therewith, said driving mechanism including a longitudinally extending drive shaft connected with said motor, the forward end of said shaft being provided with a drive connection to a shaft perpendicular thereto having a drive sprocket mounted thereon for driving a cutter chain about a cutter arm, means carried on said cutter head for rotating said cutter arm about the axis of rotation of the latter shaft into a plurality of cutting positions, means cooperating with said rotating means for varying the distance between said cutter arm and the axis of rotation of said cutter head, and a longitudinally disposed feed operating shaft extending parallel to and driven from said drive shaft, and having driving connections for either said varying or rotating means. 110 115 120 125 130

2. In a mining machine, the combination of

- a wheeled frame, a turntable thereon, cutting mechanism on said turntable including a motor, a cutter head rotatably driven by said motor about an axis longitudinal of said cutting mechanism, a cutting element disposed forwardly of said cutter head, means carried on said head for rotating said cutting element about an axis perpendicular to the longitudinal axis of said cutter head, and means for varying the distance between said cutting element and the central longitudinal axis of the aforementioned cutter head comprising a shaft operatively connected to said motor and connecting the cutter head to the cutting element and selective connections between said motor and shaft for translational moving said shaft with respect to said cutter head for moving said cutting element toward or away from the longitudinal axis of said cutter head or rotating said shaft for moving said cutting element about an axis perpendicular to the longitudinal axis of said cutter head.
3. In a mining machine, a support, a chain carrying cutter arm mounted thereon, a shaft for driving said cutter chain about said cutter arm disposed perpendicularly to the longitudinal axis of said support and connecting said support with said cutter arm, means for moving said cutter arm about the axis of said shaft or toward and away from said support comprising a threaded shaft, a gear threaded on said threaded shaft and journaled in said support, a pinion keyed on the outer portion of said threaded shaft, an arcuate rack on said cutter arm meshing with said pinion, and clutch means for selectively connecting said threaded shaft with said first named gear to rotate said second named gear and move said rack and cutter arm about said gear in one position, and to release said gear from said threaded shaft in another position to permit said gear to rotate relative to said threaded shaft whereby said cutter arm is moved toward or away from said support.
4. In a mining machine, a motor, a support, a chain carrying cutter arm mounted thereon, a shaft for driving said cutter about said cutter arm chain disposed perpendicularly to the longitudinal axis of said support and connecting said support with said cutter arm, drive connections from said motor to said shaft, and means driven by said cutter chain driving means for moving said cutter arm about the axis of said cutter chain driving shaft, or towards and away from said support including a threaded shaft, a gear threaded on said threaded shaft and journaled in said support, gearing connections at the opposite end of said threaded shaft having connection with said cutter arm for swinging the latter about the axis of said cutter chain driving shaft, and clutch means for selectively connecting said threaded shaft with said gear to positively actuate said gear-
- ing connections in one position and to release said gear from said threaded shaft in another position to permit said gear to rotate relative to said screw whereby said cutter arm is moved toward or away from said support.
5. In a mining machine, the combination of a wheeled frame, a turntable thereon, a pair of trunnion supports on the forward end of said turntable, cutting mechanism supported on said trunnion supports for movement about a horizontal transverse axis including a motor, a cutter head extending forwardly of said motor, a cutting element projecting forwardly of and offset from said cutter head, means carried on said cutter head for rotating said cutting element about an axis perpendicular to the longitudinal axis of said cutter head, means cooperating with said rotating means for varying the distance between said cutting element and the central longitudinal axis of said cutter head, and yieldable adjustable supporting means engaging the rearward portion of said cutting mechanism for moving said cutting mechanism about its axis of pivotal connection to said trunnion supports.
6. In a mining machine, the combination of a wheeled frame, a turntable thereon, a pair of trunnion supports on the forward end of said turntable, cutting mechanism supported on said trunnion supports for movement about a horizontal transverse axis including a motor, a cutter head disposed forwardly of said motor for rotation about an axis extending longitudinally of said cutting mechanism, a cutting element projecting forwardly of and offset from said cutter head, means carried on said cutter head for rotating said cutting element about an axis perpendicular to the longitudinal axis of said cutter head, means cooperating with said rotating means for varying the distance between said cutting element and the central longitudinal axis of said cutter head, and yieldable adjustable supporting means engaging the rearward portion of said cutting mechanism for moving said cutting mechanism about its axis of pivotal connection to said trunnion supports.
7. In a mining machine, the combination of a wheeled frame, a turntable thereon, cutting mechanism on said turntable including a motor, a cutter head projecting beyond the limits of said turntable, a pair of parallel spaced guides extending from said cutter head, a cutting element engageable with and movable in said guides towards and away from said cutter head in a plurality of parallel planes, said cutting element having a cutter bar pivotally mounted thereon to swing about an axis perpendicular to the planes of movement of said cutting element with respect to said cutter head, a cutter chain movable about said cutter bar, means for driving

- 5 said cutter chain from said motor comprising a shaft coaxial with the pivotal axis of said cutter bar with respect to said cutting element and forwardly of said guides, and
 10 means for moving said cutting element towards and away from said cutter head comprising a single threaded member on a line midway between said guides and forwardly of said aforementioned shaft.
11. In a mining machine, a motor, a support, a cutter arm having a cutter chain movable thereabout, a shaft for driving said cutter chain from said motor interposed between said support and cutter arm perpendicular to the longitudinal axis of said support, and means operable independently of said cutter chain drive shaft for moving said cutter arm towards and away from said support or about the axis of said cutter chain driving shaft
- 15 comprising a screw shaft extending between said support and said cutter arm, a gear coaxial with said screw shaft and having driven connection with said motor, and means for selectively connecting said gear with said screw shaft for rotating said screw shaft or moving said screw shaft translationally with respect to said gear comprising a clutch interposed between said shaft and gear.
16. In a mining machine, a motor, a support, a cutter arm having a cutter chain movable thereabout, a shaft for driving said cutter chain from said motor interposed between said support and cutter arm perpendicular to the longitudinal axis of said support, and means driven by said motor independently of said cutter chain drive shaft for moving said cutter arm towards and away from said support or about the axis of said cutter chain driving shaft comprising a gear held in said support for rotatable movement with respect thereto, a screw shaft supported by said gear and extending between said support and cutter arm, means for selectively connecting said screw shaft with said gear for rotating said screw shaft or moving said screw shaft translationally with respect to said gear, means for connecting said screw shaft with said cutter arm for moving said cutter arm with said screw shaft upon translational movement thereof and means for rotating said cutter arm about the axis of said cutter chain driving shaft comprising a spur gear fixed to said screw shaft adjacent the end opposite said first mentioned gear and having direct connection with gear teeth secured to said cutter arm.
17. In a mining machine, a motor, a support, a cutter arm having a cutter chain movable thereabout, a shaft for driving said cutter chain from said motor interposed between said support and cutter arm perpendicular to the longitudinal axis of said support, and means driven by said motor independently of said cutter chain drive shaft for moving said cutter arm towards and away from said support or about the axis of said cutter chain driving shaft comprising a gear held in said support for rotatable movement with respect thereto, a screw shaft supported by said gear and extending between said support and cutter arm, means for selectively connecting said screw shaft with said gear for rotating said screw shaft or moving said screw shaft translationally with respect to said gear, means for connecting said screw shaft with said cutter arm for moving said cutter arm with said screw shaft upon translational movement thereof and means for rotating said cutter arm about the axis of said cutter chain driving shaft comprising a rack having connection with said cutter arm and a spur gear fixed to said screw shaft adjacent the end opposite said first mentioned gear having its teeth engageable with the teeth of said rack.
18. In a mining machine, the combination of a wheeled frame, cutting mechanism on said wheeled frame including a motor having a cutter head extending forwardly therefrom beyond the forward limits of said wheeled frame, a cutting element offset from said cutter head movable towards and away from said cutter head including a projecting cutter arm having a cutter chain movable thereabout, drive means connecting said cutter head with said cutting element for driving said cutter chain from said motor in all positions of said cutting element with respect to said cutter head, and extensible means disposed forwardly of said cutter chain drive means for moving said cutting element towards and away from said cutter head.
19. In a mining machine, the combination of a wheeled frame, cutting mechanism on said wheeled frame including a motor having a cutter head extending forwardly there-

from beyond the forward limits of said wheeled frame, a cutting element offset from said cutter head movable towards and away from said cutter head including a projecting cutter arm having a cutter chain movable thereabout, drive means connecting said cutter head with said cutting element for driving said cutter chain from said motor in all positions of said cutting element with

5 10 respect to said cutter head, and means disposed forwardly of said cutter chain drive means for moving said cutting element towards and away from said cutter head comprising a single threaded member on the longitudinal center line of said cutter head having connection with said cutter head and cutting element.

14. In a mining machine, the combination of a wheeled frame, cutting mechanism on 20 said wheeled frame including a motor having a cutter head extending forwardly therefrom beyond the forward limits of said wheeled frame, a cutting element offset from said cutter head movable towards and away 25 from said cutter head including a projecting cutter arm having a cutter chain movable thereabout, drive means connecting said cutter head with said cutting element for driving said cutter chain from said motor in all 30 positions of said cutting element with respect to said cutter head, and extensible means driven by said motor disposed forwardly of said cutter chain drive means for moving said cutting element towards and away from said cutter head.

15. In a mining machine, the combination of a wheeled frame, cutting mechanism on said wheeled frame including a motor having a cutter head extending forwardly therefrom beyond the forward limits of said wheeled frame, a cutting element offset from said cutter head movable towards and away from said cutter head including a projecting cutter arm having a cutter chain movable 40 thereabout, drive means connecting said cutter head with said cutting element for driving said cutter chain from said motor in all positions of said cutting element with respect to said cutter head, and means driven by said 45 motor disposed forwardly of said cutter chain drive means for moving said cutting element towards and away from said cutter head comprising a single threaded member on the longitudinal center line of said cutter head having connection with said cutter head and cutting element.

16. In a mining machine, the combination of a wheeled frame, cutting mechanism on said wheeled frame including a motor having 50 a cutter head extending forwardly therefrom beyond the forward limits of said wheeled frame, a plurality of parallel spaced guides extending from said cutter head, a cutting element offset from said cutter head and movable towards and away from said cutter head

55 in said parallel spaced guides including a projecting cutter arm having a cutter chain movable thereabout, drive means connecting said cutter head with said cutting element for driving said cutter chain from said motor in all positions of said cutting element with respect to said cutter head and extensible means disposed forwardly of said drive means for moving said cutting element towards and away from said cutter head. 70 75

17. In a mining machine, the combination of a wheeled frame, cutting mechanism on said wheeled frame including a motor having a cutter head extending forwardly therefrom beyond the forward limits of said wheeled frame, a plurality of parallel spaced guides extending from said cutter head, a cutting element offset from said cutter head and movable towards and away from said cutter head in said parallel spaced guides including a projecting cutter arm having a cutter chain movable thereabout, drive means connecting said cutter head with said cutting element for driving said cutter chain from said motor in all positions of said cutting element with respect to said cutter head and means disposed forwardly of said drive means for moving said cutting element towards and away from said cutter head comprising a single threaded member on the longitudinal center line of said cutter head having connection with said cutter head and cutting element. 80 85 90 95

18. In a mining machine, the combination of a wheeled frame, cutting mechanism on said wheeled frame including a motor having a cutter head extending forwardly therefrom beyond the forward limits of said wheeled frame, a plurality of parallel spaced guides extending from said cutter head, a cutting element offset from said cutter head and movable towards and away from said cutter head in said parallel spaced guides including a projecting cutter arm having a cutter chain movable thereabout, drive means connecting said cutter head with said cutting element for driving said cutter chain from said motor in all positions of said cutting element with respect to said cutter head and extensible means driven by said motor disposed forwardly of said cutter chain drive means for moving said cutting element towards and away from said cutter head. 100 105 110

19. In a mining machine, the combination of a wheeled frame, cutting mechanism on said wheeled frame including a motor having a cutter head extending forwardly therefrom beyond the forward limits of said wheeled frame, a plurality of parallel spaced guides extending from said cutter head, a cutting element offset from said cutter head and movable towards and away from said cutter head in said parallel spaced guides including a projecting cutter arm having a cutter chain movable thereabout, drive means 120 125 130

connecting said cutter head with said cutting element for driving said cutter chain from said motor in all positions of said cutting element with respect to said cutter head and means driven by said motor disposed forwardly of said cutter chain drive means for moving said cutting element towards and away from said cutter head comprising a single threaded member on the longitudinal center line of said cutter head having connection with said cutter head and cutting element.

20. In a mining machine, the combination of a wheeled frame, cutting mechanism thereon including a motor, a cutter head forwardly of said motor extending beyond the boundaries of said wheeled frame, a cutting element having a projecting cutter arm extending forwardly therefrom movable towards

25 and away from said cutter head, a cutter chain sprocket, a cutter chain driven by said sprocket about said cutter arm, a drive connection from said motor to said cutter chain sprocket including a shaft perpendicular to

25 the longitudinal axis of said cutter head, means disposed forwardly of said shaft for moving said cutting element and cutter arm towards and away from said cutter head including a threaded shaft, and a drive connection

30 from said motor to said threaded shaft for moving said shaft with respect to said cutter head comprising a worm gear operatively connected with said threaded shaft, a worm meshing with said worm gear, and a shaft ex-

35 tending longitudinally rearwardly of said worm gear having operative connection with said worm and having selective connection with said motor.

21. In a mining machine, the combination of a wheeled frame, cutting mechanism thereon including a motor, a cutter head forwardly of said motor extending beyond the boundaries of said wheeled frame, a cutting element having a projecting cutter arm ex-

45 tending forwardly therefrom movable towards and away from said cutter head, a cutter chain sprocket, a cutter chain on said cutter arm driven by said cutter chain sprocket, a drive connection from said motor

50 to said cutter chain sprocket comprising a shaft extending longitudinally of said cutter head driven by said motor, a bevel gear driven by said shaft and a shaft having slid- able connection with said bevel gear and

55 driven thereby, and means disposed forwardly of said shaft for moving said cutting element and cutter arm towards and away from said cutter head including a threaded shaft interposed between said cutting ele-

60 ment and cutter head and having selective connection with said motor.

22. In a mining machine, the combination of a wheeled frame, cutting mechanism thereon including a motor, a cutter head forwardly

65 of said motor extending beyond the bound-

aries of said wheeled frame, a cutting element having a projecting cutter arm extending forwardly therefrom movable towards and away from said cutter head, a cutter chain sprocket, a cutter chain driven by said sprocket about said cutter arm, a drive connection from said motor to said cutter chain sprocket comprising a shaft extending longitudinally of said cutter head driven by said motor, a bevel gear driven by said shaft and a shaft having slid- able connection with said bevel gear and driven thereby and means disposed forwardly of said shaft for moving said cutting element and cutter arm towards and away from said cutter head including a threaded shaft interposed between said cutting element and cutter head and having selective connection with said shaft extending longitudinally of said cutter head.

23. In a mining machine, the combination of a wheeled frame, cutting mechanism thereon including a motor, a cutter head disposed forwardly of said motor extending beyond the boundaries of said wheeled frame, a cutting element having a projecting cutter arm extending forwardly therefrom movable towards and away from said cutter head, a cutter chain sprocket, a cutter chain driven by said sprocket about said cutter arm by said sprocket, a

45 drive connection from said motor to said cutter chain sprocket comprising a shaft ex- tending longitudinally of said cutter head and driven by said motor, a bevel gear driven by said shaft and a shaft having slid- able connection with said bevel gear and driven thereby, means disposed forwardly of said

50 last named shaft for moving said cutting element and cutter arm towards and away from said cutter head including a threaded shaft interposed between said cutting element and cutter head and a drive connection from

55 said motor to said threaded shaft for moving said threaded shaft with respect to said cutter head comprising a worm gear having operative connection with said threaded shaft, a shaft extending parallel to said first

60 mentioned longitudinally extending shaft, a worm on said shaft meshing with said worm gear and selective drive connections between said longitudinally extending parallel shafts.

24. In a mining machine, the combination of a wheeled frame, a turntable thereon, a pair of trunnion supports on said turntable, cutting mechanism supported on said trunnion supports for movement about a hori-

70 zontal transverse axis including a cutter head extending forwardly of said turntable, a projecting cutter arm supported by said cutter head for cutting adjacent the mine bottom in front of and to each side of said wheeled frame and for adjustment towards and away

75 from said cutter head, and yieldable adjustable supporting means engaging the rear- ward portion of said cutting mechanism for moving said cutting mechanism about the

- axis of said trunnion supports and adjusting the angular position of said cutter arm with respect to the mine bottom comprising a vertically movable member and yieldable compression means interposed between said vertically movable member and said cutting mechanism.
25. In a mining machine, the combination of a wheeled frame, a turntable thereon, a pair of trunnion supports on said turntable, cutting mechanism supported on said trunnion supports for movement about a horizontal transverse axis including a cutter head extending forwardly of said turntable, a projecting cutter arm supported by said cutter head for cutting adjacent the mine bottom in front of and to each side of said wheeled frame and for adjustment towards and away from said cutter head, and yieldable adjustable supporting means engaging the rearward portion of said cutting mechanism for moving said cutting mechanism about the axis of said trunnion supports and adjusting the angular position of said cutter arm with respect to the mine bottom comprising a frame member extending rearwardly of said cutting mechanism, an adjusting member guided in said frame member, yieldable compression means interposed between said adjusting member and frame member, and means supported on said turntable for vertically moving said adjusting member comprising a threaded member having engagement therewith.
28. In a mining machine, the combination of a wheeled frame, cutting mechanism on said wheeled frame including a motor having a cutter head extending forwardly therefrom beyond the forward limits of said wheeled frame, a cutting element offset from said cutter head and movable towards and away from said cutter head including a projecting cutter arm having a cutter chain movable thereabout, drive means connecting said cutter head with said cutting element for driving said cutter chain from said motor in all positions of said cutting element with respect to said cutter head, means for guiding and moving said cutting element towards and away from said cutter head comprising an extensible member disposed forwardly of said cutter chain drive means, a pair of parallel disposed guide members extending from opposite sides of said cutter head, the distance between the outer sides of said guide members being substantially greater than the width of said cutter head and said guide members being so arranged as to extend in opposite directions from the longitudinal center line of said cutter head in a plane perpendicular to the longitudinal center line of said cutter head and a pair of parallel disposed grooved guide members extending from and having connection with said cutting element, said grooved guide members having slidable engagement with said guide members on said cutter head and the total width thereof being greater than the distance between the outer sides of said guide members on said cutter head.
29. In a mining machine, the combination of a wheeled frame, cutting mechanism on said wheeled frame including a motor having a cutter head extending forwardly therefrom beyond the forward limits of said wheeled frame, a cutting element offset from said cutter head movable towards and away from said cutter head including a projecting cutter arm having a cutter chain movable thereabout, drive means connecting said cutter head with said cutting element for driving said cutter

CERTIFICATE OF CORRECTION.

Patent No. 1,891,719.

December 20, 1932.

WILLIAM T. McCULLOUGH.

It is hereby certified that error appears in the printed specification of the above numbered patent requiring correction as follows: Page 6, line 49, claim 4, strike out the word "chain" and insert the same after "cutter" in line 48; and that the said Letters Patent should be read with this correction therein that the same may conform to the record of the case in the Patent Office.

Signed and sealed this 28th day of February, A. D. 1933.
